COMBINED CABINET AND EXTENSION TABLE

Abe J. Gaines, Glencoe, Ill., assignor to Saginaw Furniture Shops, Inc., Chicago, Ill., a corporation of Michigan

Application March 28, 1956, Serial No. 40,811

Term of patent 14 years

(Cl. D33—19)

Fig. 1.

Fig. 2.

Figure 1 is a perspective view of a combined cabinet and extension table embodying my new design.

Fig. 2 is a perspective view thereof with the table element in an extended position, illustrating the smooth, uninterrupted, plane surface of the flexible top of said table element.

I claim:

The ornamental design for a combined cabinet and extension table, substantially as shown.
